FOLLOW-UP TYPE PRESSURE FLUID SERVOMOTOR

William H. Newell, New York, N. Y., assignor to The Sperry Corporation, a corporation of Delaware

Application May 17, 1945, Serial No. 594,288, which is a division of application Serial No. 534,330, May 5, 1944. Divided and this application April 16, 1948, Serial No. 21,345

1 Claim. (Cl. 121—41)

1

This invention relates to a novel and improved hydraulic follow-up system and more particularly to a servomotor construction. This application is a division of the co-pending application of William H. Newell, Serial No. 594,288, filed May 17, 1945, for Hydraulic Follow-up System, which in turn is a division of an application of Newell et al., Serial No. 534,330, filed May 5, 1944, for Automatic Gun Control System.

An object of the invention is to provide a servomotor of the above type having novel and improved details of construction and features of operation.

Although the novel features which are believed to be characteristic of this invention are pointed out more particularly in the claim appended hereto, the nature of the invention will be better understood by referring to the following description, taken in conjunction with the accompanying drawing in which a specific embodiment thereof has been set forth for purposes of illustration.

In the drawing the figure is a diagrammatic view of a servomotor embodying the present invention.

Referring to the drawing, the servomotor block 210 is shown as containing train servomotor 220, elevation servomotor 221 and a P_1 generator valve 222 which is designed to generate a fixed pressure P_1 .

The pressure P_1 is supplied by a P_1 generator valve 222 formed in the block 210 and comprising a chamber having a slide 56' provided with end surfaces 57' and 58' forming end chambers 59' and 60', respectively. The end surface 57' is formed with one-half of the area of the end surface 58' so that when the slide 56' is in balanced position the pressure within the chamber 60' will be half that within the chamber 59'.

The chamber 59' is connected to the duct 207 containing fluid under pressure P_2 by means of a passage 223. The slide 56' is formed with an annular chamber 63' which communicates through a passage 225 with the chambers 232 and 232' to supply fluid under the pressure P_1 thereto. The annular chamber 63' communicates with the chamber 60' by means of a passage 65' in the slide.

The slide 56' is provided with a reduced diameter end portion 70' terminating at the surface 57' above mentioned and has an annular end surface 71' surrounding the end portion 70'. This annular surface 71' forms with an intermediate end wall of the valve chamber an annular chamber 72'. The annular chamber 72' communicates through a passage 224 with the passage 255 containing fluid under return pressure P_0 .

Fluid under pressure P_2 is supplied to the

5 chamber 59' of the generator valve 222 from the P_2 supply duct 48 through a duct 207 and a passage 223. Return fluid at a pressure P_0 is fed to the return duct 50 from the valve chamber 72' through a passage 224 and a duct 205. Fluid under pressure P_1 is supplied from the valve chamber 60' to a passage 225.

10 The elevation servomotor 221 comprises a chamber formed in the valve block 210, containing a sleeve 230 and a slide valve 231 which is mounted for axial movement within the sleeve 230. Chambers 232 and 233 are formed at the two ends of the sleeve 230. The chamber 232 is supplied with fluid at pressure P_1 through a passage 234 which communicates with the passage 225. Chamber 233 is supplied with fluid at a pressure controlled by the operation of the slide valve 231 through a passage 235 communicating with an elongated chamber 236 in the sleeve 230.

15 The slide valve 231 is acted upon at one end by the hydraulic pressure P_1 from the chamber 232 and at its other end forms a closure for a chamber 237 formed within the bore of the sleeve 230. The slide valve 231 is acted upon by two opposed springs 238 and 239. The spring 238 extends between one end of the slide valve 231 and a ring 240 attached to the sleeve 230 within the chamber 237. The spring 239 extends between the opposite end of the slide valve 231 and a pin 241 which is mounted in a fixed plate 242 forming an end enclosure for the chamber 232. The pin 241 is adjustable for varying the tension of the spring 239. The slide valve 231 is formed with a central annular chamber 245 which communicates through a passage 246 in the sleeve 230 with the chamber 236 and is thus in communication with end chamber 233.

20 Fluid under pressure P_2 is supplied through a passage 250 from a passage 251, which communicates with the duct 207, to an elongated chamber 252 formed in the sleeve 230 and thence to a passage 253 which terminates adjacent the lower end of the chamber 245 and is normally closed by the slide valve 231.

25 Fluid at the pressure P_0 is returned from the valve 221 to the return duct 205 through a passage 255 in the valve block 210, which passage is connected to the slide valve 231 through a passage 256 in the valve block 210 leading to an elongated chamber 257 in the sleeve 230, thence through a passage 258 in the sleeve 230 which passage terminates adjacent the upper end of the chamber 245 and is normally closed by the slide valve 231. The passages 253 and 258 are so arranged that one or the other is brought into communication with the chamber 245 when the slide valve 231 moves axially from its balanced position.

Fluid under pressure P_0 is supplied from duct

31 through passage 260 in the valve block 210 to an elongated chamber 261 in the sleeve 230, thence through a passage 262 in the sleeve 230 which communicates with the chamber 237.

The link 366 which connects to the automatic computing apparatus is connected to the sleeve 230 and extends outwardly from the valve block 210.

The speed of response of the sleeve 230 to movements of the valve 231 is controlled by an adjusting screw 265 which extends into the passage 235 and controls the flow of fluid therethrough. Thus the controlling effect on the sleeve 230 of sudden changes in the controlling pressure may be eliminated to a large extent by the restricted flow through the passage 235. A stop screw 266 carried by the sleeve 230 extends into the chamber 245 to limit the axial movement of the slide valve 231 relative to the sleeve 230.

Assuming that the pressure of P_e equals the pressure P_i , then the pressure within the chamber 237 will equal the pressure in the chamber 232 and the forces on the two ends of the slide valve 231 will be balanced. The valve will then take a position at which the forces due to the springs 238 and 239 are also balanced and the sleeve 230 will be in a position relative to the slide valve 231 such that the passages 258 and 253 are both closed, as shown in the drawing.

If now the pressure P_e is assumed to increase, the pressure in chamber 237 becomes greater than the pressure (P_i) in chamber 232 and the slide valve 231 is caused to move downwardly thereby increasing the tension of spring 238. This downward movement of the slide valve 231 opens the passage 253 to the chamber 245 and allows fluid under pressure P_2 to pass from the passage 250 through the chamber 245 and the passage 235 to the chamber 233. This increases the pressure in the chamber 233 and causes the sleeve 230 to move downwardly. This action continues until the downward movement of the sleeve 230 with respect to the slide valve 231 again centers the sleeve with respect to the valve and closes the passage 253. As the sleeve 230 thus follows the movement of the valve 231, the tension of the spring 238 is restored to normal. The valve 231 and the sleeve 230 move down together, except for the effect of the restriction in passage 235 caused by the screw 265, until the tension of the spring 239 is reduced by an amount corresponding to the increase in the pressure P_e in chamber 237. Since the pressure in the chamber 232 and tension of the spring 238 remain at their normal values, the valve 231 and the sleeve 230 assume a position where the increased effect of the pressure in chamber 237 tending to move the valve 231 down is neutralized by the reduced effect of the spring 239.

The sleeve 230 accordingly not only follows the movement of the slide valve 231, but, due to the large area of the end of the sleeve 230 as compared to the area of the ends of the slide valve 231, exerts an increased force which may be applied by the link 366 to the input of a computing mechanism such as that set forth in the patent applications above identified. The ratio of the force exerted by the link 366 to that exerted upon the slide valve 231 may be varied as desired by changing the relative dimensions of the parts. Hence, the sleeve 230 may be caused to exert any necessary force upon the link 366 for actuating the computing mechanism.

As explained, the movement of the slide valve

231 and the sleeve 230 is proportional to the changes in pressure P_e . Hence the position of the link 366 represents the rate of elevation dE which is to be set into the computing mechanism.

It will be noted that the position taken by the link 366 is dependent only upon the pressure P_e and is not affected by leakage in the hydraulic system provided the leakage does not change the pressures. For any given control pressure P_e there is an exact corresponding position for the link 366 which is determined by the spring and hydraulic pressures only, provided of course the hydraulic system has sufficient capacity to keep the various passages and ducts full at the various pressures.

The elements of the train servomotor 220 are identical with those of the elevation servomotor above described and have accordingly been given

20 the same reference characters with the suffix t . Fluid under pressure P_t is supplied to the train rate amplifier valve from the duct 80 through a passage 270 in the valve block 210. This causes a movement of the slide valve 231 t which is proportional to changes in pressure P_t and a corresponding movement of the sleeve 230 t which actuates the link 355 to introduce the rate of train dBs into the computing mechanism.

Although a specific embodiment of the invention has been shown for purpose of illustration, it is to be understood that the invention is capable of various adaptations as will be readily apparent to a person skilled in the art. The invention is only to be limited in accordance with 35 the scope of the following claim.

What is claimed is:

A pressure responsive servomotor comprising a housing, a piston in said housing forming a fluid chamber at each end of the housing, a bore 40 in the piston communicating at one end with the corresponding end chamber and closed at the other end, a slide valve in said bore, springs extending between the ends of said slide valve and the closed end of said bore and said housing, respectively, a passage supplying fluid at a fixed intermediate pressure to the end chamber communicating with said bore so as to apply force to said piston and to said slide valve, a passage supplying control pressure to the chamber 45 formed between the other end of said slide valve and the closed end of said bore to displace said slide valve from its mid-position against the force of said springs, passages in said piston containing fluid under high and low pressures, respectively, terminating in ports closed by said slide valve, a passage in said piston communicating with the chamber at the other end of said piston, said slide valve having means establishing communication between said last passage and 50 said high or low pressure passages, respectively, in response to displacement of said slide valve relative to said piston so as to establish a pressure in said last chamber to cause said sleeve to follow said slide valve, and a link actuated by 55 said piston.
